VIBRATOR FOR MATERIAL HANDLING OR THE LIKE

Edwin F. Peterson, 119 Main St.,
Neponset, Ill. 61345

Filed June 11, 1968, Ser. No. 12,305

Term of patent 14 years

Int. Cl. D15—05

U.S. Cl. D55—1

FIG. 2

FIG. 1

FIG. 1 is a side and partial top perspective view of a vibrator for material handling or the like showing my new design;

FIG. 2 is an end perspective view thereof taken from the right of FIG. 1;

FIG. 3 is an end perspective view thereof taken from the left of FIG. 1; and

FIG. 4 is a side and end perspective view thereof taken approximately from the rear of FIG. 1.

I claim:

The ornamental design for a vibrator for material handling or the like, substantially as shown.
